UNITED STATES PATENT OFFICE.

ALBEN E. LUNDELL AND EDGAR H. CLARK, OF NEW YORK, N. Y., ASSIGNEES TO
WESTERN ELECTRIC COMPANY, INCORPORATED, OF NEW YORK, N. Y., A COR-
PORATION OF NEW YORK.

TELEPHONE-EXCHANGE SYSTEM.

Application filed September 6, 1919. Serial No. 322,039.

To all whom it may concern:

Be it known that we, ALBEN E. LUNDELL and EDGAR H. CLARK, citizens of the United States, residing at New York, in the county of Bronx, State of New York, and at New York, in the county of New York and State of New York, respectively, have invented certain new and useful Improvements in Telephone-Exchange Systems, of which the following is a full, clear, concise, and exact description.

This invention relates to telephone exchange systems, and more particularly to improvements in systems employing machine switching.

An object of this invention is to provide improved and simplified means for controlling continuous trunk hunting in automatic switches.

Another object is to provide simple means for varying the size of groups of trunks over which continuous hunting is to take place.

According to one feature of the invention, a pair of relays are arranged jointly to control the action of a third relay and to control the continuous hunting movement of the switch over groups of variable size. The third relay is also responsive to the electrical condition of the terminals over which hunting occurs, and acts to stop the switch when a desired set is reached.

Heretofore, in switches which provided for continuous trunk hunting, it has been the practice to design the structure to permit hunting over groups each containing a fixed number of terminals. When traffic increased so that the number of terminals in a group was not sufficient to handle the calls, and it was desired to increase the number in each group, changes were necessary in the structure of the switch. According to the present invention, no structural change is necessary to vary the size of the groups, but only a slight circuit change.

The drawing is a diagrammatic representation of an embodiment of the invention applied to a telephone exchange system employing switches of the panel type, but it is to be understood that the invention is not limited in its scope to such sys-

tems but might readily be applied to systems employing any form of machine switching.

At the left of the dotted line, in the drawing, is shown in abbreviated form, apparatus at a substation a central office operator's cord circuit and a district selector switch S for connecting the substation to the incoming selector S'. These selector switches may be of the panel type fully disclosed in the patent to Craft and Reynolds No. 1,123,696 of January 5, 1915.

Within the dotted rectangle, a sender is shown. Only an upper zero counting relay 1, a stepping relay 2 and a sequence switch contact 3 of the sender are shown herein. The contact 3 is controlled by a sequence switch (not shown) associated with the sender, which is in turn controlled through the front contact and armature of relay 1. The other sequence switch contacts indicated to the left of the dotted line are controlled by the district selector sequence switch (not shown). The sequence switch contact indicated to the right of the dotted line are controlled by sequence switch 100.

The sequence switches referred to may be of the type disclosed in the patent to Reynolds and Baldwin No. 1,127,808 of February 9, 1915. The circuits employed in operating the sender and district selector are fully disclosed in the patent to Lundell No. 1,168,319 of January 18, 1916.

It is believed that the invention will be readily understood from the following description of the operation of the system.

A subscriber at station A desiring a connection, removes his receiver from the switchhook and completes a circuit for the line relay 5 which lights the call lamp 6 before an operator. The operator noticing the lamp 6, inserts her plug 8 in the answering jack 9, and inquires the desired number. The insertion of plug 8 into jack 9, completes a circuit for relays 7 and 10. Relay 7 cuts off the line relay and extinguishes the call lamp. The relay 10 starts the district selector sequence switch, the contacts of which are indicated at the left-hand side of the dotted line. Under the control of this sequence switch, the sender is associated with the district selector S and the operator

now sets the selector in accordance with the number of the called line. The brushes 13, 14 and 15 of the district selector are then set in the well-known manner on the terminals 16, 17 and 18 of an idle trunk leading to the incoming selector S', in the banks of which are terminals of trunks leading to switches through which a connection with the desired line may be completed.

- 10 After the setting of the selector S, its sequence switch will be in position 7. A circuit is thereupon completed from grounded battery, through the winding of relay 4, sequence switch contacts 19 and 20, conductor 21, sequence switch contact 3, winding of stepping relay 2, back contact and armature of relay 1 to ground. Relay 4 is energized and locks up over a circuit through its right-hand front contact and armature, sequence switch contact 22, and the circuit just traced. Relay 4 in energizing, moves the district selector sequence switch, out of position 7 into position 8. A circuit is thereupon completed from ground, left-hand armature and front contact of relay 4, contact 23, brush 13, terminal 16, conductor 56, contact 24, conductor 25, contact 26, through the right-hand winding of line relay 27 to grounded battery. Line relay 27 is energized in this circuit and locked up through its right-hand armature, conductor 28, contact 29, contact 30, conductor 25, through the circuit just traced to ground, at the left-hand armature of relay 4. In energizing, relay 27 completes a circuit from grounded battery, power magnet of sequence switch 100, contact 31, front contact and inner left-hand armature of relay 27 to ground, to drive the sequence switch 100 out of position 1, into position 2 under the control of its master contact 32. In position 2 of sequence switch 100, a circuit is completed for the up-drive magnet 33 of the incoming selector switch S', which may be traced from grounded battery, magnet 33, back contact and outer right-hand armature of relay 34, contact 36, front contact and inner left-hand armature of relay 27 to ground. Magnet 33, in operating, presses driving ribbon 37 against a roller 38 which is constantly rotating in the direction indicated by the arrow, to elevate brush rod 39, with its associated sets of brushes. Each time that the brush 47 passes a conducting segment of commutator 50, ground is connected over the following path: brush 47, commutator 50, contact 54, conductor 55, terminal 17, brush 14, contact 58. This ground holds up relay 4, but shunts stepping relay 2 to operate the counting relays in the well-known manner. When the last counting relay 1 is energized, the fundamental circuit is broken at the armature and back contact of relay 1 and relay 4 deenergizes to move the district selector sequence switch into position 9. At

its left-hand armature, relay 4 opens the circuit of relay 27 which deenergizes, opening the circuit of magnet 33 and stopping the switch. In deenergizing, relay 27 moves sequence switch 100 into position 3 over a 70 circuit from grounded battery, power magnet of sequence switch 100, contact 59, back contact and outer left-hand armature of relay 27, conductor 60, contact 61 to ground.

The desired set of brushes, of which only 75 one set 40, 41 and 42 is shown, is now in position to be tripped, and the trip rod magnet 62 is energized over a path from grounded battery, winding of magnet 62, contact 63 to ground, so that the brushes 80 will be tripped upon the next upward movement of the brush rod 39.

With the district sequence switch in position 9, a circuit is again completed for relay 4 which energizes and locks up over the 85 path previously traced. In energizing relay 4 moves the district sequence switch into position 10. A circuit is then completed from grounded battery, through the right-hand winding of relay 27, contact 26, and 90 the circuit previously traced to ground, at the left-hand front contact and armature of relay 4. Relay 27 energizes and locks up in the manner previously described. A circuit is now completed from grounded battery, 95 winding of sequence switch 100, contact 31, front contact and inner left-hand armature of relay 27 to ground, to move sequence switch 100 out of position 3, into position 4. In position 4, the circuit for 100 up-drive magnet 33 is again completed as before, the selected set of brushes 40, 41 and 42 are tripped so as to engage terminals 43, 44 and 45, respectively, and group selection takes place. Each time that the 105 brush 47 passes over a conducting segment of commutator 50, ground is applied over the circuit previously traced to shunt stepping relay 2, until relay 1 again operates to break the fundamental circuit and to deenergize 110 relay 4. As before, relay 27 deenergizes to move sequence switch 100 into position 5, and to open the circuit of magnet 33. The test brush 42 is now in engagement with an intermediate terminal 46, just below the 115 terminals of the group of trunks leading to the desired final selector switches.

With the sequence switch 100 in position 5, a circuit is completed to energize relay 27 from grounded battery, left-hand winding of relay 27, contact 64, back contact and outer right-hand armature of relay 35, back contact and inner right-hand armature of relay 34 to ground. Relay 27 in energizing, completes a circuit previously traced to 125 move sequence switch 100 out of position 5 into position 6. In position 6, the circuit of up-drive magnet 33 is again completed to drive the brushes over the terminals in the selected group, to seek an idle trunk, which 130

will be distinguished by absence of potential, the busy trunks being distinguished by ground potential. Line relay 27 locks up over a circuit from grounded battery, 5 through its right-hand winding, front contact and armature, conductor 28, contact 29, contact 65, test conductor 66, brush 42 and test terminals 45 of busy trunks. As soon as the brushes start upward, brush 48 10 leaves the insulating segment of commutator 51, upon which it was resting, and a circuit is completed from ground, brush 48, conducting segment of commutator 51, conductor 67, contact 68, conductor 69, left-hand armature and back contact of relay 34, winding of relay 35, through the right-hand winding of relay 34 to grounded battery. Relay 35 is energized in this circuit, but relay 34 is not, since its right-hand 20 winding is marginal, and will not pull up the relay but serves only as a holding winding. Relay 35, in energizing, breaks the circuit over which the left-hand winding of relay 27 was energized and leaves the 25 line relay 27 under the control of the test circuit.

If now there is an idle trunk in the group being hunted over, the circuit through the right-hand winding of relay 27 will be 30 broken when its terminals are reached. Relay 27 is held up for a moment longer, however, over a circuit from grounded battery, left-hand winding of relay 27, contact 70, conductor 71, conducting segment of commutator 52 and brush 49 to ground. When brush 49 leaves the conducting segment of commutator 52, this circuit is broken and relay 27 deenergizes, breaking at its inner left-hand armature and front contact the 35 circuit of the updrive magnet 33, and stopping the switch with its brushes in engagement with the terminals of an idle trunk. The insulating segments of the commutator 52 are so positioned, that the brush 49 will 40 only rest on one, when brushes 40, 41 and 42 are accurately centered on a set of terminals 43, 44 and 45. Relay 27 in deenergizing completes a circuit from ground, inner right-hand armature and back contact of 45 relay 34, outer right-hand armature and front contact of relay 35, conductor 72, conductor 60, contact 83, contact 84, back contact and right-hand armature of relay 27, conductor 28, contact 29, contact 65, test 50 brush 42 and test terminal 45 of the selected trunk. This application of ground to the test conductor of the seized trunk, renders this trunk busy immediately upon its seizure. It will be remembered that relay 35 was 55 energized during the upward travel of the brushes, so that upon deenergization of relay 27, a circuit is completed from grounded battery, magnet of sequence switch 100, contact 59, back contact and 60 outer left-hand armature of relay 27, con-

ductor 72, front contact and outer right-hand armature of relay 35, back contact and inner right-hand armature of relay 34 to ground, to move sequence switch 100 out of position 6, into position 7. In position 7, the circuit of relay 35 is broken at contact 68 and it deenergizes to complete a circuit from grounded battery, left-hand winding of relay 27, contact 64, back contact and outer right-hand armature of relay 35, back contact and inner right-hand armature of relay 34 to ground. Relay 27 is energized and locked up over a circuit from grounded battery, right-hand winding, front contact and armature of relay 27, conductor 28, contact 29, contact 73, over the test conductor 57, terminal 18, and brush 15 to the ground which was connected to this brush, when the district selector switch S was set. In energizing, relay 27 completes a circuit from grounded battery, power magnet of sequence switch 100, contact 31, front contact and inner left-hand armature of relay 27 to ground, to move sequence switch 100 into position 8. In position 8, the sender is again operated in the well-known manner to set the final selector switch on the terminals of the desired line. Conversation may now take place. At the close of the conversation, the operator is 90 notified in the well-known manner through the operation of supervisory relays 11 and 12, and removes plug 8, from jack 9. In so doing, she restores the district selector switch S, thus removing the holding ground from the brush 15 and line relay 27, which deenergizes. In deenergizing, relay 27 completes a circuit from grounded battery, power magnet of sequence switch 100, contact 59, back contact and outer left-hand armature of relay 27, conductor 60, contact 61 to ground, to move sequence switch 100 into position 18. In position 18, a circuit for the down-drive magnet 74 is completed from grounded battery, winding of magnet 74, contact 75, to ground. The magnet 74 is energized and presses the driving ribbon 37 against the constantly-rotating roller 76 to restore the brush rod and brushes to normal position. When this 110 position is reached, a circuit is closed from grounded battery, magnet of sequence switch 100, conductor 77, contact 78, commutator 79, brush 47 to ground, to move sequence switch 100 out of position 18, back 115 to normal, at which time the system is ready for the next call.

It will be remembered that hunting for an idle trunk began with sequence switch 100 in position 6, with relay 27 locked up through its right-hand winding to test brush 42 and the test terminals of busy lines and with relay 35 energized over a circuit extending from a conducting segment of commutator 51 and conductor 67, 130

through the winding of relay 35, right-hand marginal winding of relay 34 to grounded battery. When relay 35 was energized, a circuit was prepared for the left-hand winding of relay 34 from ground, contact 80, front contact and left-hand armature of relay 35, through the left-hand winding of relay 34, winding of relay 35, right-hand winding of relay 34 to grounded battery. Relay 34 does not pull up during upward travel of the bushes, however, since this circuit is shunted by a ground applied through the left-hand armature and back contact of relay 34. If no idle trunk is found, brush set 40, 41 and 42 will continue its travel until an intermediate terminal such as 46, at the end of the group, is reached. In passing from the last busy test terminal 45 of the group tested, to the intermediate terminal 46 which is distinguished by absence of potential, brush 42 breaks the holding circuit through the right-hand winding of relay 27. This relay deenergizes, opening at its inner left-hand armature the circuit for up-drive magnet 33 and stopping the switch. Brush 48 comes to rest on an insulating segment of commutator 51, thus removing the shunt from the left-hand winding of relay 34, whereupon this relay is energized in series with relay 35 over the circuit prepared when relay 35 was energized. Relay 34 energizes so soon after the deenergization of relay 27, that the circuit which was momentarily closed for the power magnet of sequence switch 100 over the back contact and outer left-hand armature of relay 27 is ineffective. A circuit is now completed from grounded battery, left-hand winding of relay 27, contact 64, front contacts and inner right-hand armatures of relay 35 and relay 34 to ground, to energize relay 27. This relay completes the circuit of down-drive magnet 74 from grounded battery, winding of magnet 74, front contact and outer right-hand armature of relay 34, contact 36, front contact and inner left-hand armature of relay 27 to ground. Magnet 74 is energized and carries the brushes downward over the group of trunk terminals. As soon as brush 48 leaves the insulating segment of commutator 51, upon which it was resting, a circuit is completed from ground, brush 48, commutator 51, conductor 67, contact 68, left-hand armature and front contact of relay 34, right-hand winding of relay 34, to grounded battery, thus shunting the left-hand winding of relay 34 and winding of relay 35. Relay 35 deenergizes, but the right-hand winding of relay 34 is sufficient to hold up this relay. In deenergizing, relay 35 opened the circuit through the left-hand winding of relay 27 and transferred the control of this relay to its right-hand winding, which is locked up to ground on

busy terminals. If an idle terminal is now found, the circuit through the right-hand winding of relay 27 is broken, due to absence of potential on test contacts of idle lines. Relay 27 is held up momentarily over a circuit from grounded battery, left-hand winding of relay 27, contact 70, conductor 71, conducting segment of commutator 52, brush 49 to ground, until the brushes 40, 41 and 42 are accurately centered on the idle set of terminals, at which time brush 49 reaches an insulating segment of commutator 52, opening the circuit of relay 27. Relay 27 thereupon deenergizes breaking at its left-hand armature and front contact, the circuit of down-drive magnet 74 and stopping the brushes on an idle trunk terminal. Relay 27 in deenergizing, applies ground to the test conductor of the seized trunk to hold said trunk busy, over the following circuit: ground inner right-hand armature and front contact of relay 34, inner right-hand armature and back contact of relay 35, conductor 72, conductor 60, contact 83, contact 84, back contact and right-hand armature relay 27, conductor 28, contact 29, contact 65, conductor 66, brush 42 and test terminal 45. From this point, the operation is the same as in the case previously described, when an idle terminal was found in the upward hunting movement.

If no idle terminal is found in the downward hunting movement, the brushes travel until they reach the intermediate terminal 46 at the end of the group, at which time the holding circuit of relay 27 is broken as previously described. As the brush 48 comes to rest on an insulating segment of commutator 51 immediately after the deenergization of relay 27, the holding circuit through the right-hand winding of relay 34, its front contact and left-hand armature and conductor 67 is broken at said insulating segment and relay 34 deenergizes. Relays 34 and 35 are now both in deenergized condition, the brushes are resting on the intermediate terminal at the bottom of the group of terminals which are to be hunted over, and the condition of the system is exactly the same as described when sequence switch 100 first reached position 6. Relay 27 is again energized through its left-hand winding and the back contacts and right-hand armatures of relays 35 and 34, and hunting is continued until an idle trunk is found, on either the up or down movement of the brush shaft.

We have so far assumed that only one group of terminals is to be hunted over continuously, regardless of whether any idle terminals are found or not. When traffic conditions become so heavy that it frequently occurs that no idle trunk will be found in a group of terminals of the size

originally designed to be hunted over, the group of terminals to be hunted over may be enlarged to twice its original size, or as many times more as is desirable, by simply connecting ground to intermediate test terminals 46 between the groups of terminals which are to be consolidated into a single group, no ground, however, will appear on the terminals 46 which are to define the limits of the new group.

The operation up to the time when sequence switch 100 moves into position 6 is the same as described for the smaller group of terminals. When sequence switch 100 is in position 6, the circuit is completed from grounded battery, left-hand winding of relay 27, contact 64, back contact and outer right-hand armature of relay 35, back contact, inner right-hand armature of relay 34 to ground to energize relay 27. Relay 27, in coming up, completes the circuit for up-drive magnet 33 and locks up through its right-hand winding, front contact and armature to ground at busy test terminals 45, as before. Ground is applied through the brush 48, conducting segment of commutator 51, to the left-hand armature and back contact of relay 34, as before, and relay 35 is energized. If an idle trunk is found in the first sub-group hunted over, relay 27 deenergizes as before, to stop the switch. If no idle trunk is found, the intermediate terminal 46 being now grounded, holds up relay 27 to continue the travel of the brushes into the next sub-group. Brush 48 encounters an insulating segment of commutator 51 as before but removal of the ground connected from brush 48 and the conducting segment of commutator 51 to the left-hand armature and back contact of relay 34 does not, however, remove the shunt from the left winding of this relay, as in the case previously described, since a substitute shunt circuit is provided traceable from ground, inner right-hand armature and back contact of relay 34, outer right-hand armature and front contact of relay 35, conductor 72, outer left-hand armature and front contact of relay 27, contact 82, contact 68, conductor 59, back contact and left-hand armature of relay 34. Thus relay 35 is held energized throughout the upward travel of the brushes and relay 34 has an energizing circuit prepared to operate at the removal of the ground through commutator 51 when an insulating segment of said commutator is reached by brush 48, at a time when relay 27 is deenergized. If no idle terminal is found throughout the entire enlarged group, the brushes travel upward until the intermediate terminal 46, at the end of the group, is reached, at which time no potential being found at terminal 46, the holding circuit for relay 27 is broken to deenergize this relay. Relay 27, in deenergizing, breaks at

its outer left-hand armature and front contact the circuit which held up relay 35 when the intermediate insulating segments of commutator 51, were being passed over. Since there is now no ground at the left-hand armature of relay 34 to shunt its left-hand winding, this relay comes up in series with relay 35 over the circuit from grounded battery, right-hand winding of relay 34, winding of relay 35, left-hand winding of relay 34, left-hand armature and contact of relay 35, contact 80 to ground. The left-hand winding of relay 27 is now energized over the circuit extending through the front contacts and right-hand armatures of relays 35 and 34, as previously described, and the circuit of down-drive magnet 74 is also completed over the previously traced circuit. As soon as brush 48 leaves the insulating segment of commutator 51, ground is applied over the circuit previously traced through the left-hand armature and front contact of relay 34, to hold up this relay and to shunt relay 35 which deenergizes. When subsequent insulating segments of commutator 51 are traversed, a substitute circuit to hold up relay 34 may be traced from grounded battery, right-hand winding of relay 34, front contact and left-hand armature of relay 34, conductor 69, contact 68, contact 82, outer left-hand armature and front contact of relay 27, conductor 72, back contact and inner right-hand armature of relay 35, front contact and inner right-hand armature of relay 34 to ground. Thus, relay 34 is held up until this holding circuit is broken by the deenergization of relay 27, caused by the finding of an idle set of trunk terminals or of an intermediate test contact 46 at the end of the enlarged group which is distinguished by absence of potential. It will thus be seen that the number of terminals in a group which is to be hunted over continuously, may be changed without changing the structure of the switch, by the simple application of ground potential to intermediate test terminals 46, between groups which it is desired to consolidate into a single group.

What is claimed is:

1. In a telephone system, telephone lines, an automatic switch in which said lines terminate in groups of fixed contacts, contacts intermediate said groups of contacts, means for moving said switch back and forth over contacts of a group, and means responsive to the electrical condition of said intermediate contacts for determining whether the back and forth movement is to extend over one or a plurality of said groups.
2. In a telephone system, an automatic switch, a plurality of telephone lines divided into groups terminating in fixed contacts in said switch, contacts intermediate

said groups, means for moving said switch in a continuous reciprocating movement over said contacts to hunt an idle line, and means operating in response to the electrical condition of said intermediate contacts for limiting the movement of said switch in one direction.

3. In a telephone system, a selector switch having a directive and an automatic movement, a plurality of trunk lines accessible to said switch, means for directly setting said switch, means for automatically moving said switch back and forth in a continuous reciprocating movement to hunt an idle 10 trunk, and electrical means for varying the number of lines passed over by said switch in its hunting movement.

4. In a telephone system, telephone lines, an automatic switch in which said lines terminate in contacts, brushes arranged to travel over and make contact therewith, a source of power, a relay, a circuit for operating said relay to associate said source of power with said brushes to move them in one direction, a circuit for holding said relay operated while contacts in one electrical condition are being passed, means for interrupting said first mentioned circuit when said holding circuit becomes effective, means 20 for interrupting said holding circuit when a contact in a different electrical condition is reached, means for interrupting said holding circuit when a predetermined number of contacts have been passed, and means 25 thereupon actuated for completing said original circuit to operate said relay to associate said source of power with said brushes to move them in the opposite direction.

5. In a telephone system, telephone lines, an automatic switch in which said lines terminate in contacts, brushes cooperating with said contacts, a power circuit, a relay to control said power circuit, a pair of relays and a circuit arrangement therefor including a 40 break point whereby two successive closures and openings of said break point will cause said relays to be successively actuated in all possible combinations, a circuit for said power controlling relay alternately closed 45 and opened in successive combinations of actuation of said pair of relays, means for initially closing said circuit, a second circuit for said power controlling relay responsive to the electrical condition of said contacts, a source of power for moving said 50 brushes in one direction, a source of power for moving said brushes in the opposite direction, means responsive to the condition of one of said pair of relays for including 55 alternately said first source of power or said second source of power in said power circuit, and means positioned in accordance with the 60 position of said brushes for successively closing and opening said break point.

6. In a telephone system, telephone lines,

an automatic switch in which said lines terminate in contacts, brushes arranged to travel over and make contact therewith, a source of power, a relay, means for operating said relay to associate said source of power with said brushes to move them in one direction, means actuated when a predetermined number of said contacts have been passed to operate said relay as a result of the engagement of said brushes with a particular contact set to dissociate said source of power from said brushes, and means thereupon actuated for operating said relay to associate said source of power with said brushes to move them in the opposite direction. 75 80

7. In a telephone system, telephone lines, an automatic switch in which said lines terminate in groups of fixed contacts, contacts intermediate said groups of contacts, means 85 for moving said switch over a group of contacts, and means controlled by the electrical condition of said intermediate contacts for continuing the travel of the switch or for reversing its movement. 90

8. In a telephone system, telephone lines, an automatic switch in which said lines terminate in contacts, means for moving said switch over a predetermined number of said contacts in a continuous reciprocating motion, and means responsive to the electrical condition of certain of said contacts for continuing the movement of said switch or for reversing its movement. 95

9. In a telephone system, groups of trunk lines, an automatic switch in which said lines terminate in contacts, a contact intermediate adjacent groups of trunk contacts, means for moving said switch in a continuous reciprocating motion over a single group 100 of trunk contacts, and means controlled by the electrical condition of said intermediate contact for extending said movement over an adjacent group of contacts. 105

10. In a telephone system, equivalent and non-equivalent groups of trunks, an automatic switch in which said trunks terminate with the terminals of equivalent groups adjacent, a contact intermediate said groups, means for moving said switch over each non-equivalent group of terminals in a continuous reciprocating motion and means controlled by the electrical condition of said intermediate contact for continuing the travel of said switch over and adjacent group 115 of equivalent trunk terminals. 120

11. In a telephone system, a switch having a non-numerical movement, a plurality of telephone lines terminating in said switch, a set of wipers arranged in operative relation 125 to said lines, a source of power for moving said wipers, means for applying said source of power to move said wipers in one direction, means for disconnecting said source of power from said wipers, means for there- 130

upon applying said source of power to move said wipers in an opposite direction, means for causing said wipers to seize an electrically distinguished one of said telephone lines while moving in either direction, and electrical means for varying the number of said lines over which said wipers may move in either direction before initiation of movement in the opposite direction.

10 12. In a telephone system, equivalent and non-equivalent groups of trunks, an automatic switch in which said equivalent and non-equivalent trunks terminate with the terminals of equivalent groups adjacent, contacts intermediate each group of trunks, brushes for said switch for contacting with said terminals, a source of power, a relay, a circuit for operating said relay to apply power to drive the switch, a circuit including a contact between equivalent groups and said relay closed to maintain said source of power applied to continue the movement of the switch, and means for opening said circuit to render said relay inert to stop the

switch when the contact between non-equivalent groups is reached. 25

13. In a telephone system, equivalent and non-equivalent groups of trunks, an automatic switch in which said trunks terminate with the terminals of equivalent groups adjacent, means including control relays for moving said switch, a circuit for maintaining the control relays in a certain condition during the movement of the switch, means for opening the circuit when the end of a group is reached to change the condition of said control relays to reverse the direction of movement, and means for closing a substitute circuit to maintain the control relays in condition to keep the switch moving in the same direction to test the equivalent group when the switch reaches the end of a group preceding an equivalent group. 30 35 40

In witness whereof, we hereunto subscribe our names this 4th day of September A. D., 1919. 45
